UNITED STATES PATENT OFFICE.

JOHN M. KROYER, OF STOCKTON, CALIFORNIA.

DUST-EXCLUDING MEANS FOR EXPLOSIVE-MOTORS.

1,200,202.

Specification of Letters Patent.

Patented Oct. 3, 1916.

Application filed November 2, 1915. Serial No. 59,304.

To all whom it may concern:

Be it known that I, JOHN M. KROYER, a citizen of the United States, residing at Stockton, in the county of San Joaquin, State of California, have invented certain new and useful Improvements in Dust-Excluding Means for Explosive-Motors; and I do declare the following to be a full, clear, and exact description of the same, reference 10 being had to the accompanying drawings, and to the characters of reference marked thereon, which form a part of this application.

This invention relates to improvements 15 in attachments for explosive motors, the object of the invention being to produce a means for keeping the air which is admitted to the internal mechanism of the motor both above and below the pistons, entirely 20 free from dust or grit.

In explosive motors a great deal of dust and dirt is sucked in through the carbureter inlet and also (and this latter is the most injurious of the two) the air taken in through 25 the "breather" hole of the crank case is full of dirt and dust which tends to cut out the bearings and wearing parts of the motor. This is especially true of the motors of tractors, especially those used for drawing 30 farming implements where a great amount of dirt and dust is continually agitated and blown around the vicinity of the motor.

My improved invention is designed to 35 serve the double purpose of keeping the air admitted to the carbureter of the motor and also that admitted to the "breather" hole of the crank case entirely free from dirt, grit and dust or other deleterious 40 matter.

A further object of the invention is to produce a simple and inexpensive device and yet one which will be exceedingly effective for the purposes for which it is de- 45 signed.

These objects I accomplish by means of such structure and relative arrangement of parts as will fully appear by a perusal of the following specification and claims.

50 In the drawings similar characters of reference indicate corresponding parts in the several views.

Figure 1 is a side elevation of a motor showing my improved attachment con-

nected therewith. Fig. 2 is a sectional view of the cleanser receptacle.

Referring now more particularly to the characters of reference on the drawings, the numeral 1 designates the motor, 2, the air intake of the carbureter, and 3, the 60 "breather" hole.

My improved device comprises primarily a receptacle 4 having a suitable drain bottom 5 having a drain plug 6. Extending through the bottom of the receptacle 4 is 65 an air inlet pipe 7 which projects upwardly into the receptacle 4.

The numeral 8 designates water or other cleansing material which is filled part way into the receptacle 4 slightly below the top 70 level of the pipe 7. This level is maintained by reason of a test pet cock 9 in the side wall of the receptacle 4 near the level of the upper end of the pipe 7 through which any overflow of the material 8 may be drawn off 75 from the receptacle 4. Disposed on the top level of the material 8 and sinking part way below the level is a float 10 which surrounds the upper end of the pipe 7 in spaced relation thereto. Projecting upwardly from the 80 float 10 is an inclosed chamber or receptacle 11 into which the upper end of the pipe 7 opens. The upper end of the receptacle 4 is provided with an outlet 12 connected by a pipe 13 with the air inlet of the carbureter, 85 while the numeral 14 designates another outlet connected by a pipe 15 with the "breather" hole 3 of the crank case of the motor 1. The outlet 14 is provided with a hinged flat check valve 16 for a purpose as 90 will presently appear.

In practice the air to be taken into the carbureter and also into the "breather" hole is drawn through the pipe 7 and into the float chamber 11. From there it is 95 sucked down through the space between the float 10 and the pipe 7 and through the water or other liquid 8, and thence out of the water into the receptacle 4 and then out through the openings 12 and 14 to the carbureter and to the crank case. There will naturally be a greater suction through the opening 12 than through the opening 14, and this will tend to hold the flat valve 16 open for a brief period. During this brief period, a slight amount of the air will be drawn through the opening 14, but when the tendency to vacuum in the

crank case overcomes the suction through the outlet 12 this valve 16 will be drawn closed. By reason of this operation, while a sufficient amount of air will be admitted 5 to the crank case to sufficiently overcome the vacuum, still enough vacuum will be left to prevent suction through the member 12 from holding the valve 16 open and allowing particles of grease, dirt, and other matter to 10 be drawn from the crank case into the receptacle 4. By reason of the air all passing through the fluid 8, the same will be relieved of dirt, dust and other deleterious matter which would tend to cut the bearings and 15 wearing parts of the motor.

Depending downwardly from the member 11 and into the pipe 7 is an indicator rod 17, which, when the level of the material 8 becomes too low, will project below the bottom 20 of the receptacle to indicate this fact, whereupon the receptacle can be refilled through an upper removable plug 18. When the material 8 becomes overcharged with dirt, dust or other deleterious matter, the 25 same may be drawn off through the bottom by removing the plug 6. On the float 10 is a projecting flange 19 provided with a plurality of leather or similar bumpers 20 arranged for striking the sides of the receptacle 4 to maintain the substantial central position of the float within the said receptacle. If from any cause excess pressure should accumulate within the receptacle 4, it would relieve itself by pushing through 30 the material 8 into the chamber 11 and thence out the pipes 7.

From the foregoing description it will be

readily seen that I have produced such a device as substantially fulfills the objects of the invention as set forth herein. 40

While this specification sets forth in detail the present and preferred construction of the device, still in practice such deviations from such detail may be resorted to as do not form a departure from the spirit of 45 the invention, as defined by the appended claims.

Having thus described my invention what I claim as new and useful and desire to secure by Letters Patent, is:

1. The combination with an explosive motor, of an air cleanser, a pipe leading from the cleanser to the "breather" hole in the crank case of the motor, and means for maintaining a suction from the cleanser independently of that through the pipe connected with the crank case. 55

2. The combination with an explosive motor, of an air cleanser, and a pipe leading from the cleanser to the air intake of the carbureter of the motor, and another pipe leading from the cleanser to the "breather" hole in the crank case of the motor, as described. 60

3. The combination with an explosive motor, of an air cleanser provided with a pair of outlets, one outlet being connected with the air intake of the carbureter of the motor, and the other being connected with the "breather" hole of the crank case of the 70 motor, and a check valve interposed over the last named outlet, as described.

In testimony whereof I affix my signature.
JOHN M. KROYER.
